UNITED STATES PATENT OFFICE.

HASKELL K. MEACHAM, OF ABILENE, TEXAS.

DESIGN FOR A MILITARY UNIFORM.

59,502.

Specification for Design.

Patented Oct. 25, 1921.

Application filed May 10, 1921. Serial No. 468,435. Term of patent 14 years.

To all whom it may concern:

Be it known that I, HASKELL K. MEACHAM, a citizen of the United States, residing at Abilene, in the county of Taylor and State of Texas, have invented a new, original, and ornamental Design for a Military Uniform, of which the following is a specification, reference being had to the accompanying drawings, forming a part thereof.

The figure is a perspective view of the uniform showing my new design.

I claim:

The ornamental design for a military uniform, as shown.

HASKELL K. MEACHAM.
